UNITED STATES PATENT OFFICE.

FRED W. STAIR, OF CHICAGO, ILLINOIS.

DESIGN FOR A WIND-DEFLECTOR CLAMP.

57,021.

Specification for Design.

Patented Jan. 25, 1921.

Application filed July 28, 1920. Serial No. 399,634. Term of patent 7 years.

To all whom it may concern:

Be it known that I, FRED W. STAIR, a citizen of the United States, residing at Chicago, county of Cook, and State of Illinois, have invented a new, original, and ornamental Design for a Wind-Deflector Clamp, of which the following is a specification, reference being had to the accompanying drawing, forming a part hereof, in which—

The figure is a perspective view of my clamp.

I claim:

The ornamental design for a wind deflector clamp, as shown.

FRED W. STAIR.
